AUTOMATIC SAWMILL SET WORKS

John H. Thedick, Klamath Falls, Oreg., assignor to Klamath Machine & Locomotive Works, Inc., Klamath Falls, Oreg., a corporation of Oregon

Filed Feb. 19, 1958, Ser. No. 716,063

10 Claims. (Cl. 143—120)

This invention relates to a set works control system of the automatic type for the control of the lateral movement of the knees of a sawmill carriage, and more particularly to a fully automatic set works control system which is operative to positively stop and lock the set shaft precisely at the point when the carriage knees have reached their desired points of adjustment.

It has been conventional in the past in the sawmill industry for two men to be employed for the operation of a given sawmill carriage. One, the sawyer, handles the loading of the carriage and controls the travel of the carriage. The other, the setter, sets the carriage knees and controls the operation of the dogs. At the present time, it is undesirable, at least in connection with some types of sawing operations, to employ two men for one carriage, due to the high labor costs involved. For this and other reasons, a number of types of automatic set works control systems have been devised for the purpose of enabling the sawyer to perform not only his normal duties but those of the setter.

It is generally recognized that the automatic set works control systems heretofore devised leave something to be desired from the standpoints of dimensional accuracy of the lumber being sawed and of maintenance.

When two-man carriage operation was in vogue, the most accurate, rugged, and the least costly manual set works used was that known as a Trout-type set works. In the recently issued patent to Craik, No. 2,707,501, the Trout-type set works (disclosed, *inter alia*, in patents to Trout Nos. 793,406 and 995,205) is referred to as anachronistic in that it "looks and operates like an old-time streetcar motorman operating handle and shaft." Nevertheless, the Trout-type set works enabled the attainment of optimum dimensional accuracy of the lumber being sawed and very low maintenance cost.

Basically, a Trout-type set works comprises a shaft which is mounted for rotation and rotated with the set shaft, a ratchet wheel secured to the shaft to be rotated, a setting arm adapted to rotate coaxially to said ratchet wheel and provided with a grip block which can be caused to engage the ratchet wheel at predetermined positions to the effect of locking the setting arm in a given position relative to the ratchet wheel and a heavy post, or stop, member to prevent any more than the desired degree of rotation (*i.e.* the determinant of the set-out distance desired) of the ratchet wheel by engaging the grip block. This positive stop action is imparted to the set shaft, with the result that there is a positive precision control over the set-out distances desired.

Others who have been active in the art of providing automatic set works control systems for sawmill carriages have worked along the line of providing electrical and electronic drive and control systems for initiating movement of the set shaft and de-energizing said shaft, and this has necessitated the provision of complicated braking and valving systems for stopping the carriage knee set shaft at any pre-determined point. Insofar as I am aware, each such system has an inherent deficiency with respect to precision of set-out capability which is directly reflected in the accuracy of the lumber being cut.

The subject set works control system is based upon the concept of combining the precision control features of

2

the Trout-type set works with automation control means adapted to replace the human setter, thereby achieving the goal of eliminating the setter without creating a precision control problem.

An object of the present invention is to provide a Trout-type set works control system which will be operable from a remote control panel.

Another object of this invention is to provide a Trout-type set works control system which is conveniently operable by the sawyer.

Other objects and advantages will be apparent from the following description when taken in conjunction with the accompanying drawings, in which:

Figure 1 is a view in side elevation, with parts broken away, of the set works control column and related control means;

Figure 2 is a sectional view taken along lines 2—2 of Figure 1;

Figure 3 shows the upper plate of the set works control column and the control elements disposed thereon;

Figure 4 is a partial view in vertical section of the apparatus of Figure 1;

Figure 5 shows a detail of Figure 4 in a different operative position;

Figure 6 is a detail view taken along lines 6—6 of Figure 4;

Figure 7 is a semi-schematic layout of the subject control system and the circuitry therefor;

Figure 8 constitutes a wiring diagram for the set works column;

Figure 9 is a wiring diagram for the relay panel; and Figure 10 is a wiring diagram for the control panel.

With reference to the drawings in detail, and with immediate reference to Figure 1, drive shaft 10, actuated by an independent air motor (not shown) transmits its rotary movement by means of terminal bevel pinion 12 to face gear 14 and set shaft 16 connected thereto. Face gear 14, in turn, transmits its movement to pinion 18 and shaft 20 connected to said pinion. Gear box 22 supports a complex casing indicated generally at 24 and said casing serves to support the immediate control elements of the set works column phase of the control system. Ratchet wheel 26 is secured to shaft 20 by a key 27 (Figure 4).

Setting arm assembly 28 comprises a forked setting arm 30 adapted to shaft 20 for independent pivotal movement relative thereto by means (see Figure 4) comprising hub portions 32 and 34. The upper and lower forks of setting arm 30 have integral therewith outer side webs 35 which enclose a grip block 36, the latter being pivotally supported between said webs 35 by means comprising pins 38, 40, 42 and 44, link 39 interconnecting pins 38 and 40, and latch arm 43 interconnecting pins 42 and 44.

Grip block air cylinder 46 is fixedly secured to setting arm hub portion 34 and rotates therewith. Energization of said cylinder to move piston rod 47 outwardly causes toothed grip block 36 to engage toothed wheel 26 (see Figure 6) by means of link 48 pivotally connected to the piston rod 47 and to latch arm 43, the latter being pivotally mounted on pin 42. Conjoint swinging movement of arm 43 about pin 42 and of link 39 about pin 38 causes grip block 36 to be moved from its Figure 4 position to the ratchet wheel engaging position of Figure 5. Said latch arm 43 further comprises a latch element 52 affixed

65 to its lower part, the purpose of which will be subsequently related. Hub 34 further supports friction wheel 54 in fixed relation therewith, whereby two way indexing rotary movement can be imparted to the setting arm assembly 28. Housing 24 supports a set-up ring 56 (Figures 1 and

70 2) in fixed relation therewith and comprises a post 58 which has pivotally mounted therein holding pawl 60, said pawl being adapted, as hereinafter described, to be

moved into and out of holding engagement with ratchet wheel 26. Post 58 also supports for axial movement a spring loaded cushion plunger 62. Fixedly supported by post 58 is top plate 64 which in turn supports various drive and control elements, hereinafter described. Set-up ring 56 is provided with an arcuate slot 57 to permit a plurality of latch blocks 66 to be affixed to said ring at selected positions, said latch blocks being secured to said ring and being attached to indexing, or limit, switches 68 by means comprising bolts 70 and switch carrier plates 72. The latch blocks 66 are provided with centrally disposed slot guideways 67 having divergent ends whereby latch element 52 is centered and guided as it moves therethrough as the grip block 36 is moved into and out of engagement with respect to ratchet wheel 26. The indexing, or limit, switches 68 are provided with pivotally movable control arms 69. Secured to setting arm 30 is a switch arm actuator 71 adapted upon indexing movement of said setting arm to cam said control arms 69 out of the path of movement of said actuator and thereby by control the condition of said switches 68.

Means for rotating the setting arm assembly 28 in either direction of rotation comprise the aforementioned friction wheel 54, a drive roller 45 therefor secured for rotation on the output shaft 47 of reversible indexing motor 49, the latter being mounted on a plate 50 which is pivotally supported at 51 by the top plate 64. Motor shaft 47 extends through a slot formed in plate 64, thereby permitting motor mounting plate 50 to be swung in one direction to bring drive roller 45 into engagement with friction wheel 54 and to be swung in the other direction to disengage said roller from said wheel. Spring means (not shown) interconnecting plates 50 and 64 normally maintains roller 45 out of engagement with wheel 54, while the piston rod of motor hinge cylinder 73 mounted on plate 64 engages motor mounting plate 50 and pushes the latter upon being energized to cause engagement of said roller with said wheel. Cylinder 73 is under the control of an air valve 74 (Figure 3) which in turn is electrically controlled, as will hereinafter appear.

Since the principles of the Trout-type set works are well known in the art and since the present invention relates mainly to the combination therewith of remote control mechanism, only the latter will be hereinafter described in detail.

The subject control system enables the sawyer, through the medium of simple controls located at his normal station and consisting of a selector, e.g. a tap, switch for selectively controlling the position of the setting arm 30 and thumb-operable controls whereby the set shaft 16 may be rotated to any desired extent in either direction or may be rotated to set out the knees of the sawmill carriage within the precision control limitation reflected by a particular position of the setting arm, to control the operation of the remotely located set works control column whereby the following control movement of the set works can be accomplished; the knees may be retracted or advanced to the extent necessary to permit loading or turning of the log on the carriage; succeeding cuts of identical or varying thickness may be made; the setting arm will automatically index to its previously set position after a cut has been taken in the event that it is desired to take a succeeding cut of the same thickness; and a change in either direction of the index setting can be made at any time except during the setting out operation.

The preferred embodiment of the control system shown employs an air motor, not shown, and an air pressure system for driving the set works and operating various of the principal control elements.

OPERATION

Preliminary to a description of the phases of control of the subject control system, it is pointed out that said description will be primarily keyed to the semi-schematic

showing in Figure 7 of the circuitry and control elements. However, the encircled reference numbers for the leads in Figure 7 and the parts reference numbers appearing therein are set forth in the wiring diagrams of Figures 8-10 so that the details of any phase of the control operation may be traced.

(A) To advance and recede carriage knees at will

Since this phase of operation is the most elemental, 10 it will be dealt with first, as a preliminary to the more intricate aspects of the operation of the control system.

By pressing either the advance button 76 or the reverse button 78, delay relay 80 is de-energized and delay relay 82 is energized. This releases the holding pawl 60 from engagement with the ratchet wheel 26, the same being done by the introduction of a pulse into the coil of holding pawl cylinder valve 86 (Figure 3). Said valve is thereby reversed to cause holding pawl cylinder 88 (Figure 1) to move pawl 60 away from wheel 26 through the linkage assembly indicated generally at 90 (see Figures 1 and 8). Likewise, grip block 36 is released from the ratchet wheel 26 by a pulse introduced into the control coil of grip block cylinder valve 92 (Figure 7), said valve being thereby reversed to cause grip block cylinder 46, through its cylinder rod, link 48 and latch arm 43, to move the grip block out of engagement with the ratchet wheel. Air motor valve 94 is then actuated through either line ② or line ④, depending upon which of the buttons 76, 78 was pressed, to drive shaft 16. 20 When the depressed button of the pair 76, 78 is released, the air motor driving of shaft 16 is stopped (valve 94 being moved to a closed position), and holding pawl 60 and grip block 35 are reengaged with ratchet wheel 26 in that order.

30 The delay relay 82 allows the grip block and holding pawl to be dis-engaged before the air motor drive starts, and the delay relay 80 and the limit switch 96 (Figure 8), the latter being actuated by movement of the linkage 90 which serves to re-engage the pawl 60 with the ratchet wheel 26, enable the following to be accomplished in the order mentioned: the cessation of the air motor drive; engagement of the ratchet wheel by the holding pawl; and the engagement of the ratchet wheel by the grip block.

40 45 When the holding pawl 60 is brought into engagement with the ratchet wheel and while it is in engagement therewith, the red signal light 98 (Figures 7 and 10) indicates this condition, being energized through main Line L1, switch 100 (Figures 7 and 8) and line ④.

(B) To index the setting arm

With reference to Figure 10, the setting arm 30 (Figure 4) is indexed to the desired setting by turning the control knob 102 of selector, e.g., tap, switch 104 (Figure 5 10) so that the switch arm 106 engages the desired tap contact 108. By way of example, it will be here assumed that the switch arm 106 is in engagement with tap #2 (Figure 8) and that it is now to be brought into engagement with tap #4. Upon turning the control knob, relay 110 (Figures 7 and 9) is de-energized, i.e. line ② is disconnected from mainline L1 since tap #2 is no longer connected thereto (it requires the connection to mainline L1 of a given tap and a closed condition of the corresponding index, or limit, switch 68 in order to render line ② live). This causes operation of valve 92 to reverse the grip block cylinder 46, and operation of the latter causes the latch element 52 to pass outwardly through the #2 set-up block 66 (Figures 1 and 2) and releases the grip block 36 from the ratchet wheel. At the same time, the indexing motor is energized (L1, relay 110, relay 112 and ④) and drives the setting arm assembly 28 until the cam arm 71 carried thereby actuates the arm 69 of the #4 indexing, or limit, switch 68 to close said switch. Since the tap switch 104 is at the 70 #4 setting, ② is energized and relay 110 is thereby caused

to be energized. This breaks the line connection to ⑩, causing the indexing motor to stop. Energization of relay 110 allows the set-up lever latch 52 to pass through the #4 set-up block 66 and causes the grip block to engage the ratchet wheel under the action of grip block cylinder 46. Current flow in ⑩ energizes a green signal light 114 to show that indexing has been completed.

The direction of rotation of indexing motor 49 is controlled by (see Figure 10) friction arm 116, contacts 118, relays 120 and 122, and solenoid 124 which returns the friction arm 116 to normal position after indexing has been made. In the example just given where the index set up was changed from the #2 to the #4 tap, contacts 118 are maintained in connecting relation between L1 and relay 122, and hence the motor 49 is driven in the forward direction through one of lines ⑪, ⑫, while a "reduced cut" indexing in which the tap switch knob is rotated to a lower number tap causes contacts 118 to be moved out of connecting relation between L1 and relay 122, with the result that the motor 49 is reversely driven through the other of lines ⑪, ⑫.

As previously indicated, the indexing, or limit, switches 68 and the set up blocks 66 are adjustable about the set up ring 56 to determine the amount of travel of the set shaft by controlling the peripheral travel of the setting arm assembly 28 and the ratchet wheel 26. The adjustment as to set-out may be made within limits of $\frac{1}{32}$ inch, as each tooth in the ratchet wheel represents $\frac{1}{32}$ inch of travel of the carriage knees.

(C) *To set out*

Having indexed the set works for a set-out operation, setting out is accomplished by the sawyer by depressing control button 126 (Figure 7). This connects L1 and ⑩ and energizes relay 112, thereby connecting L1 to holding pawl cylinder valve 86 through relay 112, ⑩, and holding pawl cut-off switch 128. The valve causes the cylinder 88 to operate linkage 90, thereby pivoting pawl 60 out of engagement with ratchet wheel 26 and actuating air motor and light switch 100 to connect ⑩ and ⑩ together, the former being connected to valve 74 of motor hinge cylinder 73 (by way of relay 130 and ⑩) and to valve 94 (by way of relay 82 and ⑩), and the latter (⑩) being connected to L1 through relay 112. Thus, drive roller 45 is disengaged from friction wheel 54, and set shaft 16, ratchet wheel 26, and the setting arm assembly 28, which is locked to said ratchet wheel, are rotated until the setting arm assembly strikes post 58 (Figure 2). At this point, holding pawl cut-off switch 128 (Figure 7) is opened by cam 130 (Figure 3) carried by stub shaft 132 attached to the center of friction wheel 54. This actuates valve 86 (Figure 8), causing holding pawl cylinder 88 (Figure 7) to move pawl 60 into engagement with the ratchet wheel. Switch 100 is thus operated by the linkage 90 to break the connection between ⑩ and ⑩, causing valve 94 to shut off the air motor. This operation of the switch 100 connects L1 with the red signal light 98 through ⑩.

As the setting arm assembly approaches post 58, rotary cam 136 (Figure 3) carried by shaft 132 actuates restrictor valve switch 134, thereby actuating restrictor valve 138 (Figure 8) through L1, switch 134 and ⑩. This in turn actuates restrictor cylinder 140 to reduce the air flow to the air motor drive, thereby cushioning the impact of the setting arm assembly against post 58.

After the set shaft 16 has been stopped by engagement of the setting arm assembly with post 58 and the ratchet wheel has been locked against movement by the pawl 60, the set-out button 126 is released, causing the grip block to be released from the ratchet wheel and causing the indexing motor 49 to drive the setting arm assembly 28 until the indexing, or limit, switch 68 corresponding to that called for by the setting of the selector e.g., tap, switch 104 is energized by setting arm cam 71, thereby causing the grip block to be engaged with the ratchet

wheel and conditioning the control system for another set-out operation.

Exhaust valve 142 for the air motor is operated one way when the air motor drive is connected to set shaft 16 and operated reversely when said air motor drive is cut-off. Brake 144 (Figure 7) is applied to the friction wheel 54 by cylinder 146 under control of valve 148 during the occasions when the set shaft 16 is being driven forwardly or reversely at will, i.e. when the grip block is not engaged with the ratchet wheel. Hinge cylinder valve 74 operates to cause motor hinge cylinder 73 to move friction drive roller 45 out of engagement with friction wheel 26 when valve 94 is operated to initiate air motor drive.

From the foregoing it will be seen that the subject remote control set works achieves the objects of the invention initially recited herein, and while a specific and preferred embodiment of said remote control set works has been shown and described it is to be understood that said embodiment is subject to modification within the spirit of the invention and the scope of the appended claims.

What is claimed is:

1. In combination with set work means comprising a drive shaft and motive power means therefor adapted to drive set shaft means for the advancing, receding and set-out by the latter of the knee elements of a saw mill carriage, a control shaft for said drive shaft and for said set shaft means coupled thereto for rotation therewith,

30 a ratchet wheel fixedly secured to said control shaft, a setting arm assembly mounted for rotation in concentric relation to said control shaft, support means for the aforementioned elements, said assembly including a grip block mounted for movement into engagement with said

35 ratchet wheel and out of engagement therewith, and a massive stop member rigidly mounted on said support means defining the end of the path of movement of said setting arm assembly, said stop member being operable through its own fixedness and inertia, when said assembly moves into engagement with said stop member and when said grip block is in engagement with said ratchet wheel, mechanically to stop said drive shaft and set shaft means against further rotative movement; means for

40 remotely controlling the rotative movement and the degree thereof of said setting arm assembly including drive means for said setting arm assembly adapted to selectively positionally index the same relative to said ratchet wheel, and means responsive to the reaching by said setting arm assembly of such predetermined indexing position to urge said grip block into engagement with said ratchet wheel.

2. In combination with set work means comprising a drive shaft and motive power means therefor adapted to drive set shaft means for the advancing, receding and set-out by the latter of the knee elements of a saw mill carriage, a control shaft for said drive shaft and for said set shaft means coupled thereto for rotation therewith, a ratchet wheel fixedly secured to said control shaft, a setting arm assembly mounted for rotation in concentric

60 relation to said control shaft, said assembly including a grip block mounted for movement into engagement with said ratchet wheel and out of engagement therewith, and a stop member defining the end of the path of movement of said setting arm and adapted when said assembly

65 moves into engagement with said stop member and when said grip block is in engagement with said ratchet wheel to stop rotative movement of said drive shaft and set shaft means; means for remotely controlling the rotative movement and the degree thereof of said setting arm as-

70 semby comprising a motor and mounting means therefor, a plurality of selectively spaced first indexing, or limit, switches positioned on a set-up ring disposed concentrically to said ratchet wheel, trip means carried by said setting arm assembly adapted to engage and actuate

75 said switches as said assembly is rotated with the grip

block out of engagement with said ratchet wheel, a plurality of remotely located selector switches, each associated with a given one of said indexing switches, and circuit means interconnecting said indexing and selector switches, said motor, and means for moving said grip block into and out of engagement with said ratchet wheel, whereby when one of said selector switches is actuated and the indexing switch associated therewith is not actuated, said grip block is caused to be disengaged from said ratchet wheel, said motor is then energized to rotate said setting arm assembly in the direction of that indexing switch which is associated with said actuated selector switch, said trip means engages and actuates said associated indexing switch, causing said motor to be de-energized and said grip block to be moved into engagement with said ratchet wheel.

3. The remote control set works of claim 2 including a set-out control switch located adjacent said selector switches, and circuit means controlled thereby adapted when said set-out control switch is actuated and when associated ones of said indexing and selector switches are actuated to energize said motive power means and thereby said drive shaft, set shaft means and control shaft, to set-out said knee elements until said setting arm assembly is brought against said stop member.

4. The remote control set works of claim 3 including a holding pawl for said ratchet wheel, means for engaging said pawl therewith operative in response to said setting arm assembly as the latter engages said stop member, means for de-energizing said motive power means operable substantially simultaneously with the engagement of said pawl with said ratchet wheel, and means for disengaging said pawl from said wheel operable substantially simultaneously with energization of said motive power means.

5. The remote control set works of claim 4 including means operable in response to reverse actuation of said set-out control switch and to the continued actuation of said selector switch to automatically re-index said setting arm assembly to condition said set works for the subsequent actuation of said set-out control switch.

6. A Trout-type set works for a sawmill carriage comprising a control shaft operably connected to drive and set shafts, a drive motor for said shafts, a ratchet wheel fixedly secured to said control shaft for rotation therewith, a setting arm assembly including a setting grip block mounted coaxially with respect to said control shaft for rotation therewith or rotative movement relative thereto in accordance with whether said grip block is in engagement with or out of engagement with said ratchet wheel, an indexing motor and means operably relating the same to said setting arm assembly to impart rotational movement to the latter when said grip block is out of engagement with said ratchet wheel, at least one indexing, or limit, switch having an actuator disposed in the path of movement of said assembly when the latter is moved in one direction, and electrical control means including a remotely disposed selector switch, the actuation of which selector switch causes energization of said indexing motor and resulting rotative movement of said assembly, and means responsive to actuation of said indexing, or limit, switch to de-energize said indexing motor and move said grip block into engagement with said ratchet wheel, thereby indexing said set works.

7. The Trout-type set works of claim 6, said electrical control means further including a set-out switch, the actuation of which energizes said drive motor and rotates said control shaft and assembly in the other direction, a further switch in the path of movement in said other direction of said setting arm assembly, said latter switch being adapted to be actuated by engagement of said assembly therewith to de-energize said drive means and to energize means for abruptly urging a pivotally mounted pawl into holding engagement with said ratchet wheel.

8. The Trout-type set works of claim 7, said electrical control means further including means responsive to de-actuation of said set-out switch and continued actuation of said selector switch to automatically re-index said set works.

9. A Trout-type set works for a sawmill carriage comprising a control shaft operably connected to drive and set shafts, a drive motor for said shafts, a ratchet wheel fixedly secured to said control shaft for rotation therewith, a setting arm assembly, including a setting grip block movably mounted thereon, mounted coaxially with respect to said control shaft for rotation therewith or rotative movement relative thereto in accordance with whether said grip block is in engagement with or out of engagement with said ratchet wheel, a stop member defining the end of the path of set-out movement of said setting arm assembly and adapted when said assembly moves into engagement with said stop member and when said grip block is in engagement with said ratchet wheel, to stop rotative movement of said drive shaft and set shaft means, an indexing motor and means operably relating the same to said setting arm assembly to impart rotational movement to the latter when said grip block is out of engagement with said ratchet wheel, double-acting power means connected to said grip block operable to move said block relative to said setting arm assembly into and out of engagement with said ratchet wheel, electrical control means including remotely disposed selector switch means selectively operable to energize said indexing motor and rotate said assembly to a predetermined indexing station, and means responsive to the reaching by said assembly of said predetermined indexing station to actuate said double-acting power means in the direction causing movement of said grip block into engagement with said ratchet wheel.

10. A Trout-type set works for a sawmill carriage comprising a control shaft operably connected to drive and set shafts, a drive motor for said shafts, a ratchet wheel fixedly secured to said control shaft for rotation therewith, a setting arm assembly, including a setting grip block movably mounted thereon, mounted coaxially with respect to said control shaft for rotation therewith or rotative movement relative thereto in accordance with whether said grip block is in engagement with or out of engagement with said ratchet wheel, a stop member defining the end of the path of set-out movement of said setting arm assembly and adapted when said assembly moves into engagement with said stop member and when said grip block is in engagement with said ratchet wheel, to stop rotative movement of said drive shaft and set shaft means, an indexing motor and means operably relating the same to said setting arm assembly to impart rotational movement to the latter when said grip block is out of engagement with said ratchet wheel, double-acting power means connected to said grip block operable to move said block relative to said setting arm assembly into and out of engagement with said ratchet wheel, a control system including first control means selectively operable to energize said indexing motor and rotate said assembly to a predetermined indexing station and second control means operable after the reaching by said assembly of said predetermined indexing station to actuate said double-acting power means in the direction causing movement of said grip block into engagement with said ratchet wheel.
